(57) **CLAIM**

The ornamental design for a flower pot holder, as shown and described.

DESCRIPTION

FIG. 1 is a front perspective view of a first embodiment of a flower pot holder, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of a second embodiment;

FIG. 10 is a front perspective view shown in an alternative configuration of use;

FIG. 11 is a rear perspective view of the flower pot holder of FIG. 9;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof;

FIG. 18 is a front perspective view of a third embodiment;

FIG. 19 is a rear perspective view thereof;

FIG. 20 is a front view thereof;

FIG. 21 is a rear view thereof;

FIG. 22 is a left side view thereof;

FIG. 23 is a right side view thereof;

FIG. 24 is a top view thereof;

FIG. 25 is a bottom view thereof;

FIG. 26 is an enlarged detail view of area 26 in FIG. 1; and,

FIG. 27 is an enlarged detail view of area 27 in FIG. 1.

The broken lines in the drawings illustrate the portions of the flower pot holder, which form no part of the claimed design.

(Continued)

The short-long-long dash broken lines indicate cutoff boundaries for enlarged detail portion views and form no part of the claimed design.

1 Claim, 27 Drawing Sheets
